UNITED STATES PATENT OFFICE.

GEORGE FRANK WAUGH, OF THE UNITED STATES ARMY.

MATCH-BOX.

1,243,907.

Specification of Letters Patent. Patented Oct. 23, 1917.

Application filed May 29, 1917. Serial No. 171,655.

To all whom it may concern:

Be it known that I, GEORGE F. WAUGH, a citizen of the United States of America, and in the Army of the United States of America, have invented certain new and useful Improvements in Match-Boxes, of which the following is a full and clear specification.

The object of this invention is to so construct the box that one end of the main or outer casing of the box may be conveniently employed as a chamber for lighting cigars or cigarettes, as more fully hereinafter set forth.

15 In the drawings—

Figure 1 is a perspective view of my improved box showing it closed; and

Fig. 2 is a perspective view showing it partly open, the parts being positioned for 20 utilizing one end of the outer casing as a cigar-lighting chamber.

My box consists of the usual open-ended rectangular outer casing *a* and the usual tray or drawer *b* fitted thereinto and adapted to slide outwardly in either direction. On the outer face of one end wall of the tray, a suitable abrasive material *c* is applied, and in one side wall of the tubular outer casing is formed a hole *d*, this hole 30 being located a short distance from one end of the casing.

In using this box for lighting a cigar or cigarette in a wind or draft, the parts are adjusted in the position shown in Fig. 2, that 35 is, the tray is drawn out of the main box far enough to uncover the hole *d*. Then the

headed end of the match is inserted through the hole and lighted by scratching it against the abrasive material *c*. In this way the end of the main casing forms a protected 40 chamber into which the end of the cigarette or cigar may be inserted for lighting.

It will be understood, of course, that one or both the side walls of the main casing may also be provided with abrasive lighting 45 material, if desired, but it will not be necessary to do this with my box, inasmuch as the abrasive surface *c* on the end wall of the tray may be used for striking a match in the ordinary manner, if desired. In other 50 words, by utilizing the end wall of the tray as a support for the abrasive lighting material and by providing one of the walls of the main casing with a match-receiving hole, my box is made capable of being used in the 55 ordinary manner or in the manner above set forth for lighting a cigar or cigarette in the wind.

The nature and scope of the invention having been thus indicated and its preferred 60 embodiment having been specifically described, what is claimed as new is:

In a match box, a main casing open at its ends and having one of its edge walls provided with a small match-receiving hole near 65 one end, and a slidible tray fitting in the main casing and having an abrasive material applied to the outer face of that one of its end walls which is adjacent to said hole.

In testimony whereof I hereunto affix my 70 signature.

GEORGE FRANK WAUGH.
